(57) **CLAIM**

The ornamental design for the air compressor, as shown and described.

DESCRIPTION

FIG. 1 is a top-front-right perspective view of an air compressor showing my new design;

FIG. 2 is a top-rear-left perspective view;

FIG. 3 is a front elevational view;

FIG. 4 is left side elevational view.

FIG. 5 is right side elevational view;

FIG. 6 is rear elevational view; and,

FIG. 7 is a top plan view.

The broken lines are included for the purpose of illustrating portions of the air compressor that form no part of the claimed design.
